ABSTRACT

A step and repeat image reproduction apparatus for reproduction of images onto image receiving material, such as film, photosensitive material, plates or the like, from an image bearing master. The apparatus has an exposure window and a vacuum device for holding the image receiving material and the image bearing master in firm contact with the exposure window where a time controlled exposure lamp exposes the image receiving material. The image receiving material and the image bearing master are secured to slide members which are movable at right angles with each other for precisely positioning same for exposure. The image receiving material and slide member has a single linear motion, while the image bearing master and respective slide member has a single linear motion transverse to that of the image-receiving material slide member. The slide members are used conjunctively to make all necessary movements for the step and repeat exposures. A registry window has a grid therein for positioning an image bearing negative prior to being secured to a negative carrier to form the master.

STEP AND REPEAT IMAGE REPRODUCTION APPARATUS

The present invention relates to apparatus for use in the graphic arts industry and more particularly to positioning means for precisely positioning image-receiving material relative to an image-bearing master on a step and repeat apparatus.

The principal objects of the present invention are: to provide a step and repeat image reproduction apparatus having novel positioning means for precisely positioning image-receiving material relative to an image-bearing master in contact with a step and repeat vacuum apparatus; to provide such a step and repeat apparatus wherein the image-bearing master and the image-receiving material are movable at right angles with each other; to provide such a step and repeat apparatus wherein the image-bearing master is secured to a slide member movable in a linear motion and the image-receiving material is secured to a second slide member movable in a linear motion normal to the first slide member, the slide members being used in conjunction to make all necessary movements for the step and repeat exposures; to provide such a step and repeat apparatus having registry means for positioning an image-bearing negative for attachment to a negative carrier thereby forming the master; to provide such a step and repeat apparatus having visual display means for indicating precise positions of the master and image-receiving material; to provide such a step and repeat apparatus for producing camera ready sheets of copy having a plurality of images in each of a plurality of longitudinal and transverse rows; and to provide such a step and repeat apparatus which is economical to manufacture, simple and accurate in operation, durable in use, and particularly well adapted for the proposed use.

Other objects and advantages of this invention will become apparent from the following description taken in connection with the accompanying drawings wherein are set forth by way of illustration and example certain embodiments of this invention.

FIG. 1 is a perspective view of a step and repeat image reproduction apparatus embodying features of the present invention.

FIG. 2 is a plan view of the step and repeat apparatus.

FIG. 3 is a longitudinal sectional view taken on line 3—3, FIG. 2, showing a light chamber for registering and exposing images from a master onto an image-receiving material.

FIG. 4 is a transverse sectional view taken on line 4—4, FIG. 2, showing a registry guideway and adjustment means associated therewith.

FIG. 5 is an enlarged fragmentary sectional view taken on line 5—5, FIG. 2.

FIG. 6 is a fragmentary perspective view of a punch support structure with a negative carrier sheet in position to be punched.

FIG. 7 is a perspective view of an opaque negative carrier sheet held in pin registry at a registry window with opaque material being removed therefrom to form a negative receiving window in the negative carrier.

FIG. 8 is a perspective view of a completed master having an image-bearing negative secured to the negative carrier sheet.

FIG. 9 is a perspective view of the master held in pin registry at an exposure window and secured to a master positioning slide member.

FIG. 10 is a perspective view of image-receiving material held in pin registry at the exposure window with the master therebetween and showing the image-receiving material secured to a registry slide member.

FIG. 11 is a perspective view similar to FIG. 10 except showing the master and the image-receiving material in an adjusted position for exposure.

Referring more in detail to the drawings:

The reference numeral 1 generally designates a step and repeat image reproduction apparatus for producing camera ready copy which is mounted on a frame 2 having a suitable base portion 3 which is maintained in a rigid condition by

suitable bracing members 4. The base portion 3 has suitable casters 5 mounted therein to provide mobility and maneuverability of the step and repeat apparatus 1. When the step and repeat apparatus 1 is in a desired location and position, a plurality of adjustable support members, such as screws 6, are adjusted to firmly engage a suitable supporting surface, such as a floor, thereby rigidly supporting the base portion 3 and the step and repeat apparatus 1.

10 In the illustrated structure, the base portion 3 is an elongate structure having front and rear rails 7 and 8, respectively, and having end rails 9 and 10 extending between respective adjacent ends of the front and rear rails 7 and 8. The screws 6 are mounted in the front and rear rails 7 and 8 adjacent opposite ends thereof and the casters 5 are mounted in the end rails 9 and 10 adjacent opposite ends thereof.

15 Upright members 11 and 12 extend upwardly from the end rails 9 and 10, respectively, and support a table portion 15, as later described. It is desirable to provide a particularly rigid structure, therefore, gussets 16 are secured to the upright members 11 and 12 and to the end rails 9 and 10.

20 The table portion 15 has front and rear side or edge members 17 and 18, respectively, and has end edge members 19 and 20 extending between and connected to respective adjacent ends of the front and rear side members 17 and 18. A top panel 21 is secured to upper edges of the front and rear edge members 17 and 18 and to upper edges of the end edge members 19 and 20 to form a planar work surface. The top panel 21 has a work portion 22 adjacent one end edge member, as for example, member 19, and an opaque portion 23 adjacent the other end edge member 20.

25 An elongate guideway 24 is formed in an upper surface of the top panel 21 and extends longitudinally between end edges thereof and substantially parallel with the rear side or edge member 18. The guideway 24 is shaped to receive a registry slide member 25 for movement therewith, as later described. A transverse guideway 26 is formed in the upper surface of the top panel 21 and is positioned between the work portion 22 and the opaque portion 23 and extends between the front and rear side members 17 and 18. The transverse guideway 26 receives a master positioning slide member 27 for movement therewith, as later described.

30 A generally rectangular or square exposure window 28 is positioned in the work portion 22 of the top panel 21 and has a rear edge 29 adjacent and parallel with the elongate guideway 24. The exposure window 28 also has a side edge 30 adjacent and parallel with the transverse guideway 26. A generally rectangular or square registry window 31 is positioned adjacent the exposure window 28 and has a rear edge 32 adjacent and parallel with the elongate guideway 24. The rear edge 29 of the exposure window 28 and the rear edge 32 of the registry window 31 are longitudinally aligned and parallel with the elongate guideway 24.

35 The registry window 31 has a grid formed of a plurality of longitudinally spaced grid lines 33 and a plurality of transversely spaced grid lines 34 which intersect the longitudinally spaced grid lines 33 thereby forming frames for positioning respective images on an image-bearing negative 35, as later described.

40 A plurality of spaced and aligned recessed pin receiving bushings 36 are positioned adjacent the edges of the exposure window 28 and adjacent the edges of the registry window 31 for fastening various material in precise relation thereto during production of camera ready copy, as later described.

45 A punch 37 is mounted on the top panel 21 adjacent the rear side member 18 and is adapted to punch or perforate a master 38 or image-receiving material 39, as later described. The perforations are in the form of a plurality of aligned apertures 40 adjacent at least one edge of the master 38 and a plurality of aligned apertures 41 adjacent at least one edge of the image-receiving material 39, respectively. The apertures 40 and 41 are spaced and aligned to correspond to and register with the pin receiving bushings 36 adjacent the edges of the exposure window 28 and the registry window 31.

It is desirable that the punch 37 have extremely high accuracy and repeatability and automatically clamp in position material to be punched immediately prior to punching same in conjunction with the punching motion and it is desirable that the punch effectively center the material being punched, therefore, a punch corresponding to the punch disclosed in my U.S. Pat. No. 3,169,725 on Punching Apparatus Having Means to Center Workpiece is employed with the step and repeat apparatus 1.

A chamber 42 is positioned below the top panel 21 and has an exposure compartment 43 below and enclosing a lower surface of the exposure window 28. An exposure lamp 44 is positioned within the exposure compartment 43 for exposing the image-receiving material 39 thereby reproducing images from the image-bearing master 38 onto the image-receiving material 39.

The chamber 42 has a registry compartment 45 below and enclosing a lower surface of the registry window 31 and a registry lamp 46 is positioned within the registry compartment 45 for illuminating the registry window grid formed of the grid lines 33 and 34 thereby precisely positioning the image-bearing negative 35 prior to forming the master 38, as later described.

A handle 47 is mounted on the table portion 15 and is operatively connected to the registry slide member 25 for moving same along the guideway 24 to position the image-receiving material 39 relative to the image-bearing negative 35 in the master 38, as later described. In the illustrated structure, a miter gear 48 is mounted on one end of a shaft 49 extending from and turned by the handle 47. The miter gear 48 meshes with a miter gear 50 mounted on one end of an elongate gear shaft 51 having a spur gear 52 mounted on the other end thereof. The spur gear 52 is positioned to interengage with a rack gear 53 on a lower surface of the registry slide member 25 for moving same longitudinally along the guideway 24 in response to turning the handle 47. The gear shaft 51 is rotatably supported by sleeves 54, suitably supported in the chamber 42, as by being secured to and depending from the top panel 21.

A handle 55 is mounted on the table portion 15 and is operatively connected to the master positioning slide member 27 for moving same along the transverse guideway 26 to position the master 38 relative to the exposure window 28. In the illustrated structure, a shaft 56 extends downwardly through the top panel 21 and has a miter gear 57 on a lower end thereof. The miter gear 57 interengages and meshes with a miter gear 58 on one end of an elongate gear shaft 59 having a spur gear 60 on the other end thereof positioned to interengage with a rack gear 61 on a lower surface of the master positioning slide member 27 for moving same along the transverse guideway 26. The gear shaft 59 is rotatably supported by a plurality of sleeves 62 secured to and depending from the top panel 21.

A vacuum pump or motor 63 is mounted on the table portion 15 and is operative to evacuate the exposure compartment 43 by creating a vacuum therein which will hold a selected master 38 and image-receiving material 39 in firm contact with the exposure window 28. A lip or flange 15' extends inwardly from surfaces defining an opening for the exposure window 28 and suitable resilient material 65 is supported on the flanges 15'. The resilient material 65 and the material forming the exposure window 28 are spaced from the opening defining surfaces to provide for vacuum air veins 64 around the exposure window 28 for evacuating the exposure compartment and drawing the master 38 and image-receiving material 39 into firm contact with the exposure window 28. The material forming the exposure window 28 has a plurality of small parallel grooves in the upper surface thereof which communicate with the air veins 64 thereby providing vacuum means for holding the master 38 and the image-receiving material 39 in firm contact with the exposure window 28. The vacuum pump or motor 63 is activated by a switch 66 mounted on the front side member 17 for easy access thereto.

A timer 67 is operatively connected to the exposure lamp 44 positioned within the exposure compartment 43 whereby the desired duration of exposure of the image-receiving material 39 to the image or images of the image-bearing negative 35 in the master 38 may be accurately and precisely controlled by an operator (not shown). The timer 67 has a pointer 68 for indicating the duration of the exposure time and a suitable switch, such as a pushbutton 69, for activating the timer 67 and the exposure lamp 44.

10 Visual display means, such as indicators 70 and 71, are operatively engaged with the registry slide member 25 and the master positioning slide member 27, respectively, for indicating the position thereof. The indicators 70 and 71 have dials 72 and 73 respectively to visually display the position of the respective slide member with microconsecutive readout with no accumulative error and no backlash.

In using the step and repeat apparatus 1, the dials 72 and 73 are positioned at a zero initial reading. A suitable negative carrier sheet 74, such as a sheet of laminated opaque and clear material, is placed in the punch 37 where the apertures 40 are punched adjacent one side edge thereof. The negative carrier sheet 74 which will become the master 38 after securing the image-bearing negative 35 thereto is held in pin registry at the registry window 31 and adjacent a right side edge 75 thereof, as seen in FIG. 2. Pins 76 are inserted through the apertures 40 and are received in the pin receiving bushings 36 at the right side edge 75 of the registry window 31 with an enlarged head portion 77 thereof engaging the sheet 74 for accurately holding same in position. A negative receiving window 78 is formed in the negative carrier sheet 74, as by cutting through and peeling away a portion of the opaque material forming said negative carrier sheet 74. The registry lamp 46 is turned on by a suitable switch 79 mounted on the front side member

9635 9640 9645 9650 9655 9660 9665 9670 9675 9680 9685 9690 9695 9700 9705 9710 9715 9720 9725 9730 9735 9740 9745 9750 9755 9760 9765

time and the pushbutton 69 is actuated to turn on the exposure lamp 44 and activate the timer 67 for exposing the image-receiving material to the selected image on the image-bearing negative 35 of the master 38.

In the event that the image-bearing negative 35 has a plurality of images thereon to be exposed to the image-receiving material 39, the vacuum switch 66 is turned to the "off" position thereby breaking the vacuum contact between the master 38 and image-receiving material 39 with the exposure window 28. The registry slide member 25 is then moved to the next position by turning the handle 47 to position the image-receiving material 39 relative to the next image on the image-bearing negative 35. The vacuum contact is then repeated, the exposure is repeated and the vacuum contact is broken before the image-receiving material 39 is moved to align with each succeeding image in the image-bearing negative 35. This procedure is continued until the first longitudinal row is completed. The master positioning slide member 27 is then adjusted to position the image-bearing negative 35, relative to the image-receiving material 39, for a second longitudinal row of exposures, and any portion of the exposure window 28 uncovered by moving the master 38 is masked or covered, whereby the registry slide member 25 may then be adjusted to position the image-receiving material 39 in precise alignment with the images on the master 38 and the vacuum contact and exposures are accomplished in a reverse direction along the second longitudinal row. Additional rows of images and exposures will be made in the longitudinal and transverse directions by the same methods. After final exposure of the image-receiving material 39, it is removed from the apparatus 1 and processed in a normal manner. The registry slide member 25 is movable in a single linear motion in the guideway 24 and the master positioning slide member 27 is movable in a single linear motion in the transverse guideway 26 with the movements being used conjunctively to make all necessary adjustments for the step and repeat exposures.

It is to be understood that, while I have illustrated and described one form of my invention, it is not to be limited to this specific form or arrangement of parts herein described and shown.

What I claim and desire to secure by Letters Patent is:

1. A step and repeat reproduction apparatus comprising:
  - a. a planar work surface;
  - b. an exposure window in said work surface, said exposure window being translucent material;
  - c. material fastening means adjacent said exposure window for holding a master having an image to be reproduced;
  - d. an elongate guideway in said work surface adjacent said exposure window;
  - e. a registry slide member received in said guideway and movable therealong;
  - f. adjustment means engaged with said registry slide member for positioning image-receiving material secured to said registry slide member into registry with the image on said master for reproduction on said image-receiving material;
  - g. an exposure lamp below said exposure window for exposing said image-receiving material thereby reproducing the image from the master thereto;
  - h. a registry window adjacent said registry slide member;
  - i. material fastening means adjacent said registry window for holding a negative carrier sheet; and
  - j. guide means associated with said registry window for positioning an image-bearing negative for attachment to said negative carrier sheet thereby forming the master.
2. The step and repeat apparatus as set forth in claim 1 including:
  - a. a second elongate guideway in said work surface, said second guideway being adjacent said exposure window and extending transversely of said first-named guideway;
  - b. a master positioning slide member received in said second guideway and movable therealong; and
  - c. adjustment means engaged with said master positioning slide member for positioning a master secured thereto.

3. The step and repeat apparatus as set forth in claim 2 including:
  - dial indicators engaged with said respective slide members and driven by movement thereof with an absence of accumulative error and backlash to indicate linear movement of the respective slide member.
4. The step and repeat apparatus as set forth in claim 1 wherein:
  - a. said registry window is a generally rectangular area in a portion of said translucent material of said work surface; and
  - b. said registry window guide means is a grid in said registry window formed of a plurality of longitudinally and transversely spaced intersecting grid lines, said grid defining a plurality of image alignment areas for the image on said image-bearing negative.
5. The step and repeat apparatus as set forth in claim 1 wherein said exposure window fastening means and said registry window fastening means include:
  - a. punch means for perforation of said master and said image-receiving material to receive the image on said master, said perforation being a plurality of aligned apertures adjacent at least one edge of said master and said image-receiving material;
  - b. a plurality of recessed bushings adjacent at least one edge of said exposure window and adjacent at least one edge of said registry window, said recessed bushings being spaced and aligned to correspond to and register with said punched apertures in said master and said image-receiving material; and
  - c. a plurality of pins each sized and shaped to pass through said punched apertures and sized and shaped to be received in said recessed bushings thereby selectively fastening said master and said image-receiving material adjacent said exposure window and adjacent said registry window.
6. A step and repeat image reproduction apparatus comprising:
  - a. a frame having a table portion;
  - b. a top panel in said table portion;
  - c. a generally rectangular exposure window in said top panel;
  - d. fastening means associated with said exposure window for holding a master having an image to be reproduced, said master being a negative carrier sheet having an image-bearing negative secured thereto;
  - e. a first elongate guideway in said top panel, said first guideway being adjacent one edge of said exposure window and parallel thereto;
  - f. a registry slide member received in said first guideway and movable therealong;
  - g. a translucent generally rectangular registry window having one edge adjacent and parallel with said first guideway;
  - h. fastening means associated with said registry window for holding a negative carrier portion of said master;
  - i. a second elongate guideway in said top panel, said second guideway being adjacent an other edge of said exposure window and extending transversely of said first guideway and parallel with said other edge of said exposure window, said other edge of said exposure window intersecting said first-named one edge thereof;
  - j. a master positioning slide member received in said second guideway and movable therealong;
  - k. adjustment means associated with said registry slide member for positioning image-receiving material secured thereto into precise registry with the respective images on said master for reproduction on said image-receiving material;
  - l. adjustment means associated with said master positioning slide member for positioning a master secured thereto and having a plurality of rows of images to be reproduced on said image-receiving material secured to said registry slide member;

- m. an exposure lamp below said exposure window for exposing said image-receiving material thereby reproducing the image from the master thereto;
  - n. said fastening means for said exposure window and said fastening means for said registry window have a plurality of spaced and aligned recessed pin receiving bushings adjacent at least one edge of said respective windows; and
  - o. said master and said image-receiving material each have a plurality of apertures adjacent at least one edge thereof, said apertures being alignable with said pin receiving bushings whereby pins placed therein engage and hold the master and the image-receiving material.
7. A step and repeat image reproduction apparatus comprising:
- a. a frame having a table portion;
  - b. a top panel in said table portion;
  - c. a generally rectangular exposure window in said top panel;
  - d. fastening means associated with said exposure window for holding a master having an image to be reproduced, said master being a negative carrier sheet having an image-bearing negative secured thereto;
  - e. a first elongate guideway in said top panel, said first guideway being adjacent one edge of said exposure window and parallel thereto;
  - f. a registry slide member received in said first guideway and movable therealong;
  - g. a translucent generally rectangular registry window having one edge adjacent and parallel with said first guideway, said registry window having a grid formed of a plurality of longitudinally and transversely spaced intersecting grid lines, said grid forming frames for the image on said image-bearing negative;
  - h. fastening means associated with said registry window for holding a negative carrier portion of said master;
  - i. a second elongate guideway in said top panel, said second guideway being adjacent an other edge of said exposure window and extending transversely of said first guideway and parallel with said other edge of said exposure window, said other edge of said exposure window intersecting said first-named one edge thereof;
  - j. a master positioning slide member received in said second guideway and movable therealong;
  - k. adjustment means associated with said registry slide member for positioning image-receiving material secured

thereto into precise registry with the respective images on said master for reproduction on said image-receiving material;

1. adjustment means associated with said master positioning slide member for positioning a master secured thereto and having a plurality of rows of images to be reproduced on said image-receiving material secured to said registry slide member; and

- m. an exposure lamp below said exposure window for exposing said image-receiving material thereby reproducing the image from the master thereto.

8. The step and repeat apparatus as set forth in claim 7 including:

- a. vacuum means associated with said exposure window for holding said image-receiving material and said master in vacuum contact with said exposure window;
- b. a chamber below said top panel, said chamber having an exposure compartment below said exposure window and a registry compartment below said registry window, said exposure lamp being within said exposure compartment for exposing the image-receiving material thereby reproducing the image on the master to the image-receiving material;
- d. a registry lamp within said registry compartment for illuminating said registry window grid; and
- e. timing means operatively connected to said exposure lamp for controlling duration of exposure.

9. The step and repeat apparatus as set forth in claim 8 wherein:

- a. said adjustment means for said registry slide member and said adjustment means for said master positioning slide member each have gear means mounted on said respective slide member for interengagement with respective gear means mounted on an elongated shaft rotatably mounted on said table portion, said elongated shafts each having handle means mounted thereon for turning same;
- b. said fastening means for said exposure window and said fastening means for said registry window have a plurality of spaced and aligned recessed pin receiving bushings adjacent at least one edge of said respective windows; and
- c. said master and said image-receiving material each have a plurality of apertures adjacent at least one edge thereof, said apertures being alignable with said pin receiving bushings whereby pins placed therein engage and hold the master and the image-receiving material.
